GEORGE SAMUEL BAKER

By *R. H. Addams*
ATTORNEY

UNITED STATES PATENT OFFICE.

GEORGE SAMUEL BAKER, OF LONDON, ENGLAND.

BAKER'S OVEN.

1,141,601.

Specification of Letters Patent.

Patented June 1, 1915.

Original application filed March 14, 1913, Serial No. 754,340. Divided and this application filed December 26, 1913. Serial No. 808,794.

To all whom it may concern:

Be it known that I, GEORGE SAMUEL BAKER, a subject of the King of England, residing at Willesden Junction, London, 5 N. W., in England, have invented certain new and useful Improvements in and Relating to Bakers' Ovens, of which the following is a specification.

This invention relates to bakers' ovens of 10 the traveling sole plate type, and the invention comprises a novel form of automatic feeding device for introducing the goods to the baking chamber, said device including a chamber disposed adjacent the inlet end of 15 the oven and having doors at opposite ends so disposed and capable of operation that when one door is open the other is closed, said chamber also containing a conveyer by 20 which the goods are passed therethrough into the baking chamber.

The invention is hereinafter fully described and the novel features specifically pointed out in the appended claims, reference being made to the accompanying drawings which show an oven in which the present improvements have been embodied and in which:—

Figure 1 is a longitudinal section of an oven showing the baking chamber, and with 30 the automatic feed device represented diagrammatically. Fig. 2 is an enlarged longitudinal section showing the inlet end of the oven with the automatic feed device applied thereto and shown in detail.

To refer more especially to Fig. 1, *a* designates the framing or masonry of the oven which together with the flues may be of any desired or conventional form and form no part of the present invention, and *b* is the 40 baking chamber having the inlet opening *b*¹ and the discharge opening *b*². Within said baking chamber is the traveling sole plate *c*, the upper run or stretch of which constitutes the effective base of the chamber, said sole 45 plate passing at each end about polygonal rollers *c*¹, *c*² and being conducted in the course desired by guides *c*². In this figure the automatic feed device is designated as a whole by the character *e* and a discharge 50 device which forms no part of the present invention by *f*, and for a detailed illustration of the former device I will now refer to Fig. 2 of the drawings, in which there is shown in broken lines a chain prover *g* from 55 the shelves *g*¹ of which the goods to be

baked, usually in tins, are forced by a push bar *g*² onto the table *h*, said bar operating through an abutment *g*³ and series of levers *g*⁴ a knife or disk *g*⁵ which slits the goods on the table in the known manner, or they 60 may be subjected to a dusting process by flour or the like discharged through the chute *g*⁶ when required.

The automatic feed device comprises the chamber *i*, the base *i*¹ of which is shown as 65 inclined upwardly at a convenient angle to extend over the sole plate *c* and the roof or top *i*² of which makes at its rear end a close joint at *i*³ with the top of the baking chamber.

The chamber *i* is provided at the front with a rising and falling door *j* which is mounted to slide in guides *j*¹ and is operated as by rod *j*² and lever *j*³ from a cam *j*⁴ mounted on a shaft *j*⁵ carried by bearings 70 on top of the chamber. At or near the rear end of chamber *i* is a door *k* pivoted on a shaft *k*¹ and capable of being moved into the open position shown in full lines by means of the link *k*² and levers *k*³, *k*⁴, the latter actuated by a cam *k*⁵ on the aforesaid shaft *j*⁵.

The means for imparting motion to said shaft may be of any desired character, that shown however comprising a driving gear *l* on the shaft *l*¹ of which is a pinion *l*² which meshes with a spur wheel *l*³ on the cam shaft, but the cams are so disposed that when one door is open the other is shut so that as little heat and steam as possible may leak from the baking chamber when 80 introducing the goods. Within the chamber there is mounted adjacent each corner a roller *m* one of which may be adjustably mounted, and about said rollers pass two or more chains *m*¹ running in channels *m*² in 85 the side plates of the chamber and carrying at intervals transverse metal tubes, rods, or equivalents *m*³. The door *k* has an upward extension *k*⁶ which when the door is closed as shown in broken lines enters a recess *k*⁷ in 90 the top of the chamber (said recess forming a stop), and when the door is open assumes a more or less horizontal position to allow passage for the chains and rods *m*¹ and *m*³ respectively.

The operation of the automatic feed device is as follows:—The tins containing the goods to be baked are pushed off the prover shelves as described, while the latter are stationary, and during the movement of said 100 105 110

tins from the prover to the feed chamber, the forward door *j* is opening so that by the time the tins have reached said door the latter has opened sufficiently to allow them 5 to pass into the chamber *i*, the rear door *k* meanwhile remaining closed.

As soon as the tins are within the chamber the door *j* commences to close, the push bar *g*² being just clear of said door when 10 same closes, after which the chains *m*¹ commence to move forward, for which purpose one of the rollers *m* is geared by a pinion *m*⁴ to the driving gear *l*. A tube or rod *m*³ on said chains engages the rearmost tin of 15 the row and forces same forward quickly up the inclined base of the chamber toward the rear door *k* which latter swings open just in time to allow the tins to pass under, the tins being thus fed to the sole plate *c* of the 20 oven.

The chains *m* are shown as carrying two tubes or rods *m*³, and while one thereof is acting on a row of tins, the other is moving around into place to act on the next row 25 which are fed forward by the push bar *g*².

I do not limit myself to the exact construction and arrangement of parts hereinbefore described and illustrated in the accompanying drawings, since the same may 30 be varied within limits determined by the following claims without departing from the spirit of the invention.

What I claim as my invention and desire

to secure by Letters Patent of the United States is:—

35

1. In a baker's oven, an automatic feed device comprising a feed chamber, forward and rear doors for said chamber, a conveyer within said chamber adapted to engage the goods and force same through said chamber, and means for operating the forward and rear doors and conveyer in definite time relation to open the forward door, feed the goods along the chamber, close said forward door and open the rear door.

40

2. In a baker's oven, an automatic feed device comprising a feed chamber, forward and rear doors for said chamber, a conveyer within said chamber adapted to engage the goods and force same therethrough, said 50 conveyer comprising chains passing about the chamber and transverse rods or equivalents secured to said chains at intervals, and means for operating the forward and rear doors and the conveyer in definite time relation, to feed the goods along the chamber and open the forward door while the rear door is closed and vice versa.

45

In witness whereof I have signed this specification in the presence of two witnesses.

55

GEORGE SAMUEL BAKER.
